UNITED STATES PATENT OFFICE.

ALLEN A. P. NEEL, OF MARSHALL, VIRGINIA, ASSIGNOR OF ONE-HALF TO THOMAS HENDERSON MADDUX, OF MARSHALL, VIRGINIA.

STARTER FOR MOTOR-CARS.

1,126,555.

Specification of Letters Patent. Patented Jan. 26, 1915.

Application filed January 16, 1914. Serial No. 812,441.

To all whom it may concern:

Be it known that I, ALLEN A. P. NEEL, a citizen of the United States of America, residing at Marshall, in the county of 5 Fauquier and State of Virginia, have invented certain new and useful Improvements in Starters for Motor-Cars, of which the following is a specification.

This invention relates to starters for motor cars, and it proposes briefly, an improved device of the general class or character specified which will operate positively to start the motor automatically upon the mere actuation of a single rod or lever.

15 More specifically, it comprehends the provision of a starter which will act in the manner indicated without the aid of any considerable muscular effort on the part of the operator, and without requiring the employment of any such force as compressed air or gas, or electricity, but solely by the release of a spring, which latter is itself wound automatically by the motor thereby avoiding the principal defects of both types 25 of starters now in use.

Finally it contemplates the provision of a starter which shall possess maximum compactness, lightness and simplicity and which may be applied to any of the conventional 30 makes of cars without necessitating re-arrangement of the ordinary parts thereof.

An embodiment of the invention is illustrated in the accompanying drawings, wherein;

35 Figure 1 is a side elevation of the improved starter applied to the motor of a car; Fig. 2 is a vertical section of the starter; Fig. 3 is a transverse section on line 3—3 of Fig. 2; Figs. 4 and 5 are respectively an enlarged side elevation of the clutch included 40 in the starter, with parts broken away, and a transverse section of the same on line 5—5 of Fig. 4; and Fig. 6 is a sectional detail of the mounting of the starting spring.

45 Referring to said drawings and more particularly to Fig. 1 thereof 7 indicates in a general manner, the motor of the car, 8 its shaft, 9 the crank, and 10 the radiator. All of these parts or elements are of the usual 50 type and therefore, require no especial description.

The starter mechanism, wherein the invention resides, is located in the hood between the radiator and the front end of the 55 crank case of the motor and it preferably

consists, as shown, of a drum or fly-wheel 11 which is loosely mounted, by means of an axial sleeve 12 on the projecting front portion of the motor shaft 8, this sleeve being designed for endwise movement on the 60 afore-mentioned shaft portion and through or in suitable bearing brackets 13, as herein-after explained. At its front end, sleeve 12 is provided with a notch or shoulder 14 that is engageable with a tooth 15 on the motor 65 shaft to effect the rotation of the latter and in consequence the starting of the motor, when the drum is rotated, so that the parts 14 and 15 may thus be considered as the starting clutch, said parts, however, being 70 normally separated by the action of a spring 16 which is interposed between the sleeve end and the front bracket 13. Tooth 15 also co-operates in the usual way with a notch or shoulder 16' provided on the crank 75 sleeve 17, but the crank 9 is only intended to be used for starting purposes during the first operation, or setting of the mechanism, after which the mechanism will operate automatically, as will be made plain latter, 80 although the said crank may of course also be used in emergencies, as in the case of injury or accident to the starting mechanism.

The forward movement of the drum and its subsequently described connected parts, 85 for the purpose of coupling the clutch parts 14 and 15, is effected by means of a single rod 18, which, as shown, in Fig. 1, is disposed horizontally within the hood of the motor and projects at its rear end through 90 an aperture in the dash 19, at which point it is provided with a suitable handle 20. The front end of this rod 18 is pivoted to the upper end of a vertical rod 21 which has a loose pivotal connection 22, adjacent 95 its lower end, with a horizontal arm 23 that preferably constitutes an extension of the rear bracket 13, said arm 23 being secured at one end to the motor case and at the other end by a brace to the frame. The lower end 100 24 of rod 21 is forked and has a pin-and-slot connection 25 with an internally-threaded collar 26 slidable upon a short horizontal counter-shaft 27, which shaft is journaled at one end in a bearing provided in the upper portion of the rear bracket 13 and at the other end in a bushing 27' secured to the motor case, and is shiftable end-wise in and through said sleeve and bearing. The rear face of collar 26 is cupped, as 110

shown in Figs. 4 and 5, and is formed with clutch teeth 28, that are designed for co-operation with similar teeth 29 formed on the convex face of the complementary male 5 clutch member 30, which latter is fast on shaft 27 and is formed with a suitable friction gear 31. This gear 31 is designed for coaction with the concave friction face 31' of a toothed gear 31² which is loosely mounted on sleeve 27' and meshes with a toothed gear 32 fast on the motor shaft 8. The extreme inner rod portion of shaft 27 projects into a socket 27² formed in the motor case and is normally forced forward or outwardly of said socket by a spring 27³ to disengage the friction gear 31 from the friction face 31' of gear 31², as subsequently described.

The clutch members 26 and 30 act as a lock for the starting mechanism, as will be later explained, and the movable or female member 26 is normally held in engagement with the fixed or male member by means of a heavy or stiff spring 33, interposed between the former and the rear bracket 13. The gearing 31² and 32 is utilized to temporarily transmit the rotary movement of the motor shaft to the shaft 27 and for this purpose the front end of the latter is equipped 30 with a gear 34 that meshes with the internal teeth of a ring gear 35 formed on the rear face of drum 11.

The mechanism, as far as it has been described, operates substantially as follows:— Rearward movement of the main operating rod 18 effects a rocking movement of the vertical rod 21, the lower end of which latter swings or moves forward, the requisite play being provided for by the loose connection 25. As the clutch-collar 26 is held by the spring 33 firmly engaged with the clutch member 30 which is fast on shaft 27, the latter will like-wise be forced to move forward bodily and the pressure exerted 40 by its gear 34 against the rear face of drum 11 will, in turn, cause said drum and its sleeve 12 to slide forward on the motor shaft 8 until the parts 14 and 15 of the starting clutch are engaged, whereupon the forward 45 movement of the drum and sleeve will cease and the drum will be coupled to the motor shaft. The rod 18 is then pulled back still farther, with the result that the spring 33 yields and permits the disengagement of 50 the members 26 and 30 of the locking clutch. The motor is then ready to be turned over and started, but it is to be observed that the relative widths of the ring gear 35 and counter-shaft gear 34 are such that disengagement 55 of the two does not take place during the movements described.

The actual rotation of the drum is produced, according to this invention, by means of a spiral spring 36 that is fitted in a peripheral groove 37 formed in the drum, the

side walls of which groove converge toward each other as they approach the peripheral surface of the drum, as clearly shown in Fig. 6. This spring is wound up from the motor, the latter, in the initial setting of the mechanism, being cranked manually to produce the winding, which is thereafter effected automatically during the operation of the mechanism, unwinding, however, being normally prevented by the interlocking 70 of the clutch members 26 and 30. On the other hand, as soon as these members have been disengaged, the starting spring will be free to unwind and will, therefore, effect the rotation of the drum and the starting 80 of the motor, since one end of the spring in question is secured to the bracket arm 23. Owing, however, to the disposition of the spring between the converging walls of the groove 37, its expansion will be checked by 85 the contact of its convolutions with said walls, with the result that the latter will exert a retarding or braking action which will prevent too rapid unwinding.

It will be understood from the foregoing, therefore, that when the rod 18 is operated to shift the starter forward and, at the same time, to release the unlocking clutch, the expansion of the spring 36 will take place, which will in turn, rotate both the drum and 90 the motor shaft and, also, the counter-shaft 27, the rotation of the latter being due to the intermeshing of the gears 34 and 35. Now a portion of the said counter-shaft, or shiftable, locking-clutch shaft, as it may be 95 termed, is formed with a short series of threads 38, shown best in Fig. 4, which are set very close together. When the clutch-collar 26 is moved away from the clutch gear 30—31, it is brought substantially into 100 engagement with the first thread of this series, so that the rotation of the counter-shaft, which takes place immediately thereafter, will cause said collar to travel forward thereon from its full-line position to 105 its dotted line position depicted in Fig. 4, such movement, of course, being quite short and being permitted by the play provided for by the pin-and-slot or like loose connections 25. As a result of this movement, the 110 spring 33 is subjected to a compression which is utilized to produce or bring about the return movement of the counter-shaft, as will now be explained.

When the motor has commenced running, 115 the handle of the operating rod 18 is released, whereupon expansion of spring 33 forces the counter-shaft rearwardly, with the result that the friction gear 31 thereon is brought into engagement with the friction face 31' of the gear 31², the latter meshing with the gear 32 on the motor shaft, while at the same time, the drum is unclutched from tooth 15 by the action of spring 16, and returned rearward to normal position. 120 130

The rotation of the motor shaft then effects rotation of the countershaft, but in a reverse direction, due to the engagement of the gears 31² and 32, whereupon the drum, which is then loose upon the motor shaft, is likewise reversely rotated by the gears 34 and 35, thus winding up the starting spring. During this reverse rotation of the countershaft, its clutch collar travels backward and 5 becomes disengaged from the threads 38. At the same time, however, the previously tensioned spring 27³ reacts on the countershaft and forces it forward, in order to disengage the clutch member 31 from the 10 clutch face 31', of gear 31², and positively lock the former to the clutch collar, thereby locking the starting spring against unwinding. The rods 21 and 18 are likewise shifted during the return movement of the 15 collar, and means is provided for locking them in normal or neutral position at the moment when the collar leaves the rearmost thread 38, the timing of the parts being such that this disengagement of the collar 20 from said thread takes place just after the re-winding of the starting spring has been completed, thereby preventing over-winding. In the construction shown, the under surface of rod 18, adjacent to its handle 25 end, is formed with a series of notches 18' which are engageable by a suitable pawl 18² mounted on the dash.

The operation, generally, of the mechanism is believed to be apparent from the 30 above, but as far as the initial setting of the parts is concerned, it may be stated that the motor is started manually by means of the crank 9, after which the operation is automatic, with the result that the drum is 35 rotated in the proper direction to wind up the starting spring. After having once been wound up in the manner described the mechanism will proceed to operate automatically, and the car will require no further 40 manual cranking excepting in the event of injury to the starter, as previously stated.

If desired, the starter may be supplemented and further improved by the provision of a device for indicating to the 45 driver of the car the moment when the starting spring is fully wound up. Such device is represented in a somewhat diagrammatic manner in Figs. 1 and 3, and may consist, as therein shown, of a gear 39 mounted on 50 one end of a flexible shaft 40, the other end of which is connected to the pointer of an indicator or gage 41 fixed to the dash-board 19. Pinion 39 is arranged in the path of a tooth 42 provided upon the periphery of 55 drum 11, so that the revolutions of the drum incidental to the winding operation will be transmitted by shaft 40 to the indicator mechanism.

It is to be noted that in the above described mechanism the parts are free from 60

complication in construction and mode of operation; their movements are direct and positive; they can largely be made of standard material; their operation requires but little effort and there is accomplished in 70 this simple device everything accomplished in more complicated mechanisms, and in a more economical way and at necessarily less cost.

I claim as my invention:—

1. A starter for motors, comprising, in combination with the motor shaft, a drum loosely mounted on said shaft for sliding movement thereon and provided with a driving spring; means for moving said drum 80 bodily on said shaft in one direction; means for coupling said drum and shaft together when the former is thus moved; locking means for holding said spring in wound-up condition and releasable at the conclusion of 85 such movement to permit expansion of said spring and consequent rotation of said shaft; means for automatically returning said drum after such rotation has commenced; and means for re-winding said 90 spring from said shaft at the conclusion of said return movement.

2. A starter for motors, comprising, in combination with the motor shaft, a drum loosely mounted on said shaft for sliding 95 movement thereon and provided with a driving spring; a counter-shaft connected with said drum; means for moving said drum and said countershaft bodily in one direction; means for coupling said drum and the motor 100 shaft together when the former is thus moved; and a locking clutch carried by said countershaft for normally holding said spring in wound-up condition, said clutch being releasable by the first-named means at 105 the conclusion of such movement, to permit expansion of said spring and consequent rotation of said motor shaft.

3. A starter for motors, comprising, in combination with the motor shaft, a drum 110 loosely mounted on said shaft for sliding movement thereon and provided with a driving spring; a counter-shaft connected with said drum; means for moving said drum and said counter-shaft bodily in one 115 direction; means for coupling said drum and the motor shaft together when the former is thus moved; a locking clutch carried by said counter-shaft for normally holding said spring in wound-up condition, said clutch 120 being releasable by the first-named means at the conclusion of such movement, to permit expansion of the spring and consequent rotation of the motor-shaft; means for moving said drum and countershaft in the opposite 125 direction after such rotation has commenced; and a gear connection between said counter-shaft and said motor shaft for rotating the former from the latter at the conclusion of such return movement.

4. A starter for motors, comprising, in combination with the motor shaft, a drum loosely mounted on said shaft for sliding movement thereon and provided with a driving spring; a counter-shaft having a permanent gear connection with said drum and a releasable gear connection with said motor shaft; means for bodily moving said drum and said counter-shaft in one direction, whereby the second-named gear connection is released; means for coupling said drum and said motor shaft together when the former is thus moved; a locking clutch carried by said counter-shaft for normally holding said spring in wound-up condition, said clutch being releasable by the first-named means at the conclusion of such movement, to permit expansion of the spring and consequent rotation of the motor shaft; and means for moving said drum and counter-shaft in the opposite direction after such rotation has commenced, to uncouple the drum and the motor shaft and to restore the
5. A starter for motors, comprising, in combination with the motor shaft, a drum loosely mounted on said shaft and provided with a peripheral groove; a spiral spring seated in said groove; means for coupling said drum to said motor shaft; and means for locking said spring against expansion, said means being automatically releasable when said drum is coupled to said shaft to 30 permit the spring to expand, the walls of said groove converging toward the peripheral surface of said drum to retard such expansion.
